9 Claims. (Cl. 160—33)

ABSTRACT OF THE DISCLOSURE

A Venetian blind and a window opening having a recess in the upper portion for receiving the blind in collapsed position. An operator for the blind communicating with the recess and separated therefrom by a partitioning structure.

This invention relates to a building wall-and-window construction including means for controlling the passage of light through the window.

By means of the present invention a wall-and-window construction is provided whereby the light passing through the window-opening can be controlled by a conventional blind which, however, is protected against being struck or bumped by people within the building and objects which they are carrying and which blind, nevertheless, may be conveniently manipulated by those within the building. The construction and arrangement of the invention may also provide for greater shielding of the interior of the building from the heat of the sun, for guarding the blind against wind action, and for protecting the blind from dust to a considerable extent.

Various other objects and advantages relating to details and economies of manufacture, assembly and use will be apparent from the disclosure hereinafter.

In both the description and the claims parts at times may be identified by specific names for clarity and convenience but such nomenclature is to be understood as having the broadest meaning consistent with the context and with the concept of the invention as distinguished from the pertinent prior art. By way of illustration and example, the best modes thus far contemplated of carrying out the invention are illustrated in the accompanying drawings forming part of this specification. Except as may be otherwise indicated the description refers to the specific forms of the invention shown in the drawing; it does not necessarily refer to any other form in which the invention may be embodied. The claims, however, do embrace other forms in which the invention may be embodied.

FIGURES 1-7 of the drawing show a first mode that has been contemplated of carrying out the invention, and FIGURES 8-11 show a second mode that has been contemplated of carrying out the invention. FIGURE 12 shows a cover that is adaptable for use with either FIGURES 1-7 or 8-11.

FIGURE 1 is largely diagrammatic and is a fragmentary elevation, from the exterior of the building, showing a first wall-and-window construction embodying the invention including a Venetian blind in lowered position. For clarity, all of the glazing is omitted.

FIGURE 2 is the same as FIGURE 1 but with the Venetian blind in raised position.

FIGURE 3 is largely diagrammatic and is a fragmentary elevation corresponding to FIGURE 2 but from the interior of the building. A fragment of the interior glazing is shown diagrammatically.

2

FIGURE 4 is a front elevation of the blind-control unit without the cover that is illustrated in FIGURE 12, this unit being on the interior of the building.

FIGURE 5 is largely diagrammatic and is a vertical detail section, with certain parts in elevation, taken generally on the line 5—5 of FIGURE 3 and drawn to a larger scale than FIGURE 3. For clarity of illustration some parts are omitted.

FIGURE 6 is largely diagrammatic and is a horizontal detail section, taken generally on the line 6—6 of FIGURE 3. For clarity of illustration some parts are omitted.

FIGURE 7 is a detail section on the line 7—7 of FIGURE 6 showing the driving connection to the tilter of the Venetian blind.

FIGURE 8 is largely diagrammatic and is a fragmentary vertical section showing a second wall-and-window construction embodying the invention.

FIGURE 9 is a top plan view of the blind-control unit shown in FIGURE 8, standing alone and without the cover that is illustrated in FIGURE 12.

FIGURE 10 is a front elevation of the blind-control unit of FIGURE 9 looking from the bottom of that figure.

FIGURE 11 is a perspective view of the connector to the tilter of the Venetian blind.

FIGURE 12 is a perspective view of a cover that is adaptable for either the blind-control unit shown in FIGURE 4 or the blind-control unit shown in FIGURES 9 and 10.

30 The embodiment of the invention shown in FIGURES 1-7 will now be described.

In FIGURES 1-6 there is shown diagrammatically an exterior building-wall 15 of masonry, concrete or cementitious construction. The wall 15 could also be of other material, e.g., brick or wood. This wall has a vertical face 15a on the interior of the building and a vertical face 15b on the exterior of the building. A window-opening 15c extends through the wall, from the interior of the building to the exterior of the building. This window-opening has sides 15d and 15e, top 15f and a bottom 15g. The bottom 15g slopes outwardly from the interior face of the wall 15 to the exterior face thereof, giving rise to the two horizontal lines in FIGURES 1 and 2 that are respectively above and below the lead line for reference character 15g.

As is best seen in FIGURE 5, a recess 15h extends across the top 15f of the window-opening. In FIGURES 1, 2 and 3 this recess is hidden and, because of the difficulty of applying the reference character 15h to those figures, the reference character 15i is applied to the top of the recess 15h in each of FIGURES 1, 2, 3 and 5. Viewed in cross section as in FIGURE 5, the recess 15h is located between the interior and exterior faces 15a and 15b of the building-wall. This results in a partitioning structure 15j between the recess 15h and the interior of the building and another partitioning structure 15k between the recess 15h and the exterior of the building. Through the partitioning structure 15j there are passages 15m and 15n, for purposes which will appear later.

The window-opening 15c is covered by glazing, on the interior of the building and also on the exterior of the building. For convenience the term "glazing" is used to embrace not merely the transparent pane of glass or plastic but also the mounting frame therefor.

65 The interior glazing (FIGURES 3 and 5) is designated as a whole by 16 and consists essentially of a rectangular, transparent pane 16a and a rectangular mounting frame 16b. The frame 16b has a channel that is filled with

mastic or the like 16c in which the peripheral edge of the pane 16a is embedded. The frame 16b, which may be fabricated from formed metal (e.g., brass, aluminum, steel or stainless steel), may be sealed in water-excluding relation and dust-excluding relation to the window-opening in any suitable manner. As shown by way of example in FIGURE 5, the frame 16b includes an annular flange 16d which is sealed to the interior wall-surface 15a by a gasket 19. The frame 16b may be held in place by any suitable fastenings, as by a series of screws 20 (one shown in FIGURE 5). If the material of the building wall is not suitable to directly receive these screws and other screws shown for other attachments, then a screw-receiving plug or anchor may first be set into the wall for each screw, as is customary practice.

The exterior glazing is designated as a whole by 17 (FIGURE 5). This glazing will not be further described, since it is of the same construction as the interior glazing 16 and is sealed to the exterior wall surface 15b in the same manner that the interior glazing 16 is sealed to the interior wall surface 15a.

Within the window-opening 15c, and between the glazings 16 and 17, there is a Venetian blind 18; see FIGURES 1, 2, 3 and 5.

The head bar of the blind (FIGURES 6 and 5) is designated as a whole by 18a and consists essentially of an upwardly-opening sheet-steel channel 18b and operating mechanism mounted within the channel. One item of the operating mechanism is a steel tilt rod 18c. The tilt rod, which is rotatably supported by two cradles 18d (one shown in FIGURE 6), carries two sheet-steel tape rockers 18e (one shown in FIGURE 6). The upper ends of plastic or woven ladder tapes 18f and 18g (FIGURE 1) extend through slots in the bottom of the head-bar channel 18b and are attached to the tape rockers 18e. The ladder tapes carry an assembly of sheet-metal slats 18h and a sheet-steel bottom bar 18i; see particularly FIGURES 1 and 5. From the bottom bar 18i, lift cords 18j and 18k extend upwardly through rout openings in the slats, through holes in the bottom of the head-bar channel 18b and into the head bar—fragments of these two lift cords being shown in FIGURE 5. Upon the tilt rod 18c being rotated a part-turn in either direction from the position shown in FIGURES 5 and 6, the slats 18h of the blind are tilted. Upon the lift cords 18j and 18k shown in FIGURE 5 being pulled up, the blind is raised by the bottom bar 18i being pulled up and the slats 18h being accumulated on top of the bottom bar. The Venetian blind structural and operating features referred to in the instant paragraph are conventional, and will not be further described.

The head bar 18a of the Venetian blind is nested in the recess 15h (FIGURE 5) and is mounted adjacent to the top of such recess in any suitable manner. One suitable manner is to support each end of the head bar 18a with a sheet-steel installation bracket of the general type shown in U.S. patent to Lorentzen, 2,674,432, issued Apr. 4, 1954. A bracket of that general type is shown in FIGURE 5, being designated as a whole by 24. This is a separable bracket consisting of a building-attached member 24a and a detachable U-shaped stirrup 24b. The part 24a has a transversely extending straplike portion 24c which is shown attached to the top of the recess 15h by screws 25, 25. From that edge of portion 24c which is adjacent to the end of the recess 15h, there depends an integral flange 24d which is provided with a pair of screw holes 24k, 24k for, alternatively, attaching the member 24a to the end wall of the recess 15h. The ends of the member 24a are bent downwardly and thence toward each other, as shown at 24e, 24e; and the ends of the stirrup member 24b are bent outwardly in matching relationship at 24f, 24f. From the two opposite edges of each inturned portion 24e small tabs 24g extend upwardly (one shown for each inturned portion 24e).

In a typical wall-and-window construction of the present invention, the head-bar-receiving recess 15h that extends across the top of the window opening is as long as the window opening is wide, and the ends of the recess 5 15h are in alignment with the sides 15d and 15e of the window opening. The Venetian blind 18 will normally have a width only slightly less than the width of the window opening, and the head bar 18a will normally have a length sufficient to occupy the entire length of the recess 10 15h except for the small clearance needed at each end for convenient installation of the head bar. The installation bracket 24 that is shown in FIGURE 5 is of such a nature that it can be placed at different positions along the length of the head bar 18a, so that the head bar can be supported by two or more such brackets neither of which is 15 at the end of the head bar. For present purposes, however, it will be assumed that the head bar 18a is mounted by two installation brackets 24, one at each end of the head bar, which means that the brackets 24 are at the 20 ends of the recess 15h also.

The bracket members 24a having been attached to the building, one adjacent to each end of the recess 15h, any suitable manipulative procedure may be used for placing the head bar 18a and the stirrups 24b into the 25 assembled position shown in FIGURE 5. One procedure is to attach the stirrup 24b to the bracket member 24a at one end of the recess 15h, then tilt the head bar and insert the leading end thereof into that stirrup, then level the head bar, and then put the stirrup 24b into place at 30 the other end of the head bar. To enable the stirrup 24b to be assembled with the bracket member 24a after the head bar 18a has been brought upwardly against the bracket 24a, the stirrup is made long enough to provide a sufficiently loose fit vertically between the head bar 35 18a and bracket 24. With the head bar 18a pressed upwardly against the bracket member 24a, the stirrup 24b can be telescoped upwardly over the head bar while longitudinally displaced from the bracket member 24a, after which the stirrup can be shifted toward the bracket member 24a, the outturned stirrup-ends 24f passing over the tops of tabs 24g so that the stirrup can drop into the 40 assembled position shown in FIGURE 5.

For better insight into the 2-part installation bracket 45 24 and procedures that may be used for mounting a head bar with the same, see said U.S. patent to Lorentzen, 2,674,432.

A sheet-steel closure 25 (FIGURE 5) is attached to the sheet-steel bottom bar 18i in any suitable manner, as by sheet-metal screws (not shown). This closure has 50 the cross-sectional shape shown in FIGURE 5 and extends for substantially the full length of the recess 15h that is above the window opening. When the Venetian blind 18 is fully raised as shown in FIGURE 5 the closure 25 closes the recess 15h and conceals the Venetian blind. When the blind is lowered the closure 25 55 descends with the bottom bar 18i.

On the interior of the building-wall 15 there is a blind-control unit, made largely of sheet-steel stampings, that is designated as a whole by 28 (FIGURES 4, 5 and 6). This control unit has a platelike body-member 28a which supports a tilt-cord pulley 28b and a cord lock 28c. The body-member 28a, which is disposed vertically, is positioned against the interior surface 15a of the building-wall and is secured in any suitable manner as by 60 screws 28d (FIGURE 4). Extending across the top of the body-member 28a there is a horizontal flange 28e that projects forwardly from the wall-surface 15a. At the vertical edges of the body-member 28a there are flanges 28f, 28f which are displaced forwardly somewhat from the wall surface 15a as is seen in FIGURE 6. Each of the flanges 28f, 28f has a discontinuity at 28g as is seen 65 in FIGURE 4.

The blind-control unit 28 of FIGURES 4, 5 and 6 is arranged to be covered with a stamped sheet-steel cover 70 75 such as the cover 29 shown in FIGURE 12. This cover

is boxlike with an open back and bottom. Extending inwardly from the rear edges of the vertical sides 29a, 29a there are lower fingers 29b, 29b and upper fingers 29c, 29c. To mount the cover 29 the open back of the boxlike formation is passed over the cord lock 28c and the cord pulley 28b. Then the lower fingers 29b, 29b are passed through the discontinuities 28g, 28g in the vertically-extending flanges 28f, 28f of the body-member 28a. This places the upper fingers 29c, 29c above the level of the tops of the flanges 28f, 28f. Due to the displacement of the flanges 28f, 28f forwardly from the wall surface 15a, the cover 29 may now be lowered—all of the fingers 29b, 29b and 29c, 29c passing behind the flanges 28f, 28f and securing the cover 29 against forward movement. Downward movement of the cover 29 is appropriately arrested by the rear of the top 29d of the cover coming into contact with the forwardly-projecting horizontal flange 28e. To dismount the cover 29 it is slid upwardly until the lower fingers 29b, 29b match the discontinuities 29g, 29g (FIGURE 4) and then brought forwardly.

In FIGURE 12 the cover 29 is shown provided with a headed rodlike member 29e that is attached to and projects rearwardly from the front wall of the cover. The member 29e, which may be made from a solid rivet, is a stop that is omitted in some instances and, when used, has a length depending upon the normal distance between the front of cover 29b and the center of the cord pulley of the blind-control unit to which the cover is applied. In some instances the cord pulley 28b and its shaft are so related to the plate 28a of the blind-control unit that fortuitous forward movement of the pulley and shaft is prevented. In such instances the stop 29e of the cover 29 may be omitted. If, however, the cord pulley 28a and its shaft are not so related to the body member 28a as to prevent fortuitous forward movement thereof, then the stop 29e is used. The stop is positioned in alignment with the center of the cord pulley 28b, and the stop is made of such length as to place its free end closely adjacent the center of the cord pulley. Thereby the stop 29e blocks significant forward movement of the cord pulley and its shaft.

The tilt-cord pulley 28b is adapted to be rotated in either direction by a tilt cord 50, which is conveniently accessible to those within the building. Upon rotation of the pulley 28b the blind is tilted in normal manner through a suitable worm-and-gear tilter 30 (FIGURES 5 and 6) that transmits tilting movement to the D-shaped tilt rod 18c, as is well-understood. The driving connection from the pulley 28b to the tilter 30 will now be described.

Punched and drawn from the body 28a of the blind-control unit 28 there is an integral thimble 28h (FIGURES 5 and 6) into which there is press-fitted a bearing sleeve 28i. The pulley 28b is fixedly mounted on the forward end of a pulley shaft 50a in any suitable manner. The forward end of the shaft 50a may be noncircular and be of reduced diameter, passing through a mating hole in the pulley and the tip of the shaft being riveted or swaged into clamping relationship with the pulley. With the pulley 28b affixed to the shaft 50a, the shaft is assembled with the bearing sleeve 28i as shown in FIGURES 5 and 6. Then a sleeve-like connector 50b is affixed to the free end of the shaft 50a. The connector 50b is affixed to the free end of the shaft 50a in any suitable manner. The connector 50b may make a press fit with the shaft 50a, and the mating portions of the connector and shaft may be of noncircular cross section.

The tilter 30 (FIGURES 5 and 6) is of conventional internal construction and has a worm shaft 30a, which is the drive shaft or operating shaft of the tilter. In axial alignment with the shaft 30a and fixedly secured thereto, there is a sleeve-like connector 30b. The drive shaft 30a of the tilter may have a head 30c of rectangular cross section which is telescoped into the adjacent end of the con-

nector 50b, the metal of the connector being swaged against the four flat sides of the head 30c by swaging at four locations 30d (three shown in FIGURE 5 and three shown in FIGURE 6).

5 The connectors 50b and 30b are in alignment and have confronting sockets which are of D-shaped cross section, as is shown in FIGURE 7 for connector 30b. A length of steel rod 51, of D-shaped cross section, has its ends telescopically received in the D-shaped sockets of connectors 50b and 30b and makes driving connection from the connector 50b to the connector 30b. Thus, rotation of the pulley 28b by cord 50 results in rotation of the drive shaft 30a of the Venetian-blind tilter 30, with consequent tilting of the slats of the blind.

15 Different wall-and-window constructions will require rods 51 of different lengths. For use as rod 51, a length is cut from the same tilt-rod stock that is used for the D-shaped tilt rod 18c, the length cut being the length of rod 51 needed for the particular installation. With the 20 Venetian-blind head 18a mounted in the recess 15h as shown in FIGURE 5, the rod 51 is inserted through the hole 15n in the partitioning structure 15j, the leading end of the rod being telescoped into the socket of connector 30b. Then the blind-control unit 28 is mounted 25 against the interior surface 15a of the building wall, the socket of the connector 50b being telescoped over the confronting end of the rod 51.

Within the channel 18b of the Venetian-blind head bar, and mounted on the vertical wall thereof that is 30 toward the interior of the building, there is a 2-cord pulley unit 31 (FIGURES 5 and 6). For attaching this pulley unit to the channel wall any suitable means may be used, sheet-metal screws being shown. The pulley unit 31 is arranged to receive the lift cords 18j and 18k of the Venetian blind and direct them through a hole (not shown) in the wall of the channel 18b, through the hole 15m in the partitioning structure 15j, through a hole (not shown) in the body 28a of the blind-control unit 28, and thence to the cord lock 28c.

35 The cord lock 28c is conventional, having a 2-cord pulley which directs the lift cords 18j and 18k downwardly through a U-shaped sheet-steel casing within which there is a locking dog for releasably locking the cords. The cord lock shown is provided with a spring-wire separator 28s which extends between the lift cords 18j and 18k. The lift cords 18j and 18k hang within easy reach of those within the building, for manipulation to raise and lower the Venetian blind 18 in normal manner.

40 As regards the construction shown in FIGURES 8-11 it will suffice to point out the salient differences from the construction that has already been described. For parts that directly correspond to those in FIGURES 1-7 the same reference characters will be used but with 100 added thereto, e.g., 16 in FIGURE 5 and 116 in FIGURE 8.

45 In FIGURE 8 there is shown a fabricated metal framing, designated as a whole by 60, which is adapted to be set into a building wall of various constructions, e.g. wood, brick, masonry or concrete. The framing 60 provides the window opening at 115c and, above the window opening, the recess 115h in which the head bar 118a of the Venetian blind is mounted. Partitioning structure 115j is between the recess 115h and the interior of the building, and partitioning structure 115k is between the recess and the exterior of the building.

50 The window opening 115c is covered by interior glazing 116 and by exterior glazing 117. The exterior glazing is fixed, but the interior glazing 116 is hinged at 116a to afford access to the space between the two glazings.

55 Each end of the Venetian blind head bar 118a is supported by an installation bracket 124, one of which is seen in FIGURE 8. This bracket is a one-piece sheet-steel stamping, having a vertical leg 124a which is in face-to-face contact with the fixed vertical face 115e of the framing 60. The face 115e constitutes one side of the window opening 115c that is provided by the framing 60. Screws

124b, 124b pass through adjustment-slots 124c, 124c in the bracket-leg 124a and are threaded into the framing structure behind, thereby affixing the bracket 124 to the framing structure 60 in the position shown. Extending horizontally from the top of the bracket-leg 124a there is 5 a shelf that is designated as a whole by 124f. This shelf has an upwardly-opening U-shaped portion 124d in the center, which fits around the lower portion of the head bar 118a and supports the head bar. The shelf 124f also has end portions 124e, 124e which cooperate with the 10 framing structure 60 to facilitate alignment of the bracket for insertion of the screws 124b, 124b.

In the blind-control unit 128 the platelike body member 128a is formed with a forwardly-displaced U-shaped portion 128t. The portion 128t positions the tilt-cord pulley 128b forwardly whereby the depending branches of the tilt cord 150 clear the hinge at 116a as is seen in FIGURE 8. Due to the inclusion of the forwardly-displaced portion 128t in the body member 128a of the blind-control unit, the horizontal flange at the top of the 20 body member 128a is subdivided into three portions that are designated 128e, 128e' and 128e'', respectively.

The pulley shaft 150a is connected by connector 139b to the drive shaft 130a of the tilt 130. The tilt drive-shaft 130a has a slotted head 130c which receives the 25 screwdriver-like end 130k of the connector 139b. The connector 139b is a length of sheet-metal tubing one end of which is telescoped over the pulley shaft 150 in drive-fit relation therewith and the other end of which is mashed flat to provide the screwdriver-like end 130k which enters 30 the slot in the head 130c of the tilt drive-shaft. For different installations different lengths may be cut from stock tubing to make the connector 139b, whereby a pulley shaft 150a of the same length may be coupled to the drive shaft of the tilt regardless of the distance to the 35 tilt in the particular installation.

Insertion of the connector end 130k into the slot of the head 130c of the tilt drive-shaft is facilitated by a soft rubber or plastic grommet G that is set into the wall of the head channel 118b and has a funnel mouth which helps to steer the connector-end 118k toward the head 130c of the tilt drive-shaft. Once the connector-end 118k is in engagement with the head 130c of the tilt drive-shaft, the grommet G prevents lateral 40 disengagement.

In the arrangement shown in FIGURES 8 and 9 there is nothing on the shaft 150a to prevent the shaft from shifting lengthwise away from the tilt 130 and disengaging connector 139b from the tilt. However, the blind-control unit 128 is provided with a cover 129 which is the same as the cover 29 shown in FIGURE 11 except that the stop 129e is of the length that is appropriate to cooperate with the differently located pulley 128b and prevent significant forward movement thereof.

It will be seen that in the present wall-and-window construction the Venetian blind is completely out of the way, but, nevertheless, the blind can be controlled in conventional manner by those within the building to regulate the light passing through the window opening. Moreover, the glazings (16 and 17, or 116 and 117) protect the blind from dust to a considerable extent and guard the blind against wind action. In installations where protection from outside dust is considered unimportant and protection from wind action is considered unnecessary, the exterior gazing (17 or 117) may be omitted; in addition the exterior partitioning-structure (15k or 115k) may be omitted, in which case the recess at the top of the window opening will have an inner face, a top face, and two end faces but no face corresponding to the omitted partitioning-structure.

The embodiments of the invention in which an exclusive property or privilege is claimed are defined as follows:

1. A building construction comprising:

a wall through which there is a window-opening from the interior of the building to the exterior of the building;

means providing (a) a recess extending across the top of the window-opening and (b) partitioning-structure located between the recess and the interior of the building;

a Venetian blind within the window-opening, with the head bar of the blind nested in the recess at the top of the window-opening,

the blind including lift cords for raising the slats of the blind, the lift cords extending upwardly into the head bar of the blind

the blind including a tilt located in the head bar, the tilt being articulated to the slats of the blind for tilting the slats;

glazing separating the slat-assembly of the blind from the interior of the building;

and control means operable from the interior of the building to cause (a) raising and lowering of the blind and holding of the blind in vertically-adjusted position and (b) tilting of the slats of the blind,

said control means including a cord lock mounted inside of the building and separated from the head bar of the blind by said partitioning-structure,

the lift cords of the blind being reeved through an opening in the wall of the head bar, through a passage in said partitioning-structure, and downwardly through the cord lock inside of the building,

and said control means including an actuating means on the interior of the building and separated from the head bar and the tilt thereof by said partitioning-structure,

the tilt being operatively connected to said actuating means by shaft means extending through a hole in the wall of the head bar and thence through a passage in said partitioning structure to the actuating means on the interior of the building.

2. A building construction as in claim 1 in which the operating connection from the tilt to said actuating means includes a member cut to length from elongated stock, such length being according to the length of the operating connection required for the particular installation.

3. A building construction as in claim 1 in which said cord lock and said actuating means are part of a blind-control unit that is mounted on the interior of the building.

4. A building construction as in claim 1 in which said actuating means is a cord-operated tilt-pulley.

5. A building construction as in claim 4 in which the cord lock and the tilt-pulley are part of a blind-control unit that is mounted on the interior of the building and the blind-control unit is provided with a removable cover which substantially conceals the cord lock and the tilt pulley.

6. A building construction as in claim 1 in which there is partitioning-structure located between the recess and the exterior of the building, and glazing separates the slat-assembly of the blind from the exterior of the building.

7. A building construction as in claim 6 in which the actuating means of claim 1 is a cord-operated tilt-pulley.

8. A building construction as in claim 7 in which the cord lock of claim 1 and the tilt-pulley of claim 7 are part of a blind-control unit that is mounted on the interior of the building.

9. A building construction as in claim 7 in which the cord lock of claim 1 and the tilt-pulley of claim 7 are part of a blind-control unit that is mounted in the interior of the building and the blind-control unit is pro-

vided with a removable cover which substantially conceals the cord lock and the tilt-pulley.
